ABSTRACT OF THE DISCLOSURE

An implement for cutting uniform short lengths of yarn from a strip of material or yarn skein for use in making hooked rugs is disclosed. Rotation of a member causes yarn to be fed over a channeled surface beneath an oscillating blade in the rotating member and cut off at a predetermined point in each rotation. The length of the cut off pieces may be altered by insertion or removal of a collar at the hub of the rotating member.

BACKGROUND OF THE INVENTION

(1) Field of the invention

In the fabrication of hooked rugs, which are made by pulling or pushing short strips of material such as wool yarn up through a base material such as linen or burlap, the preparation of the required strips of material involves the cutting of uniform short lengths from a skein or the like. While this can, of course, be done with an ordinary pair of scissors or a knife, specialized implements have been devised for the rapid and efficient cutting of such lengths. It is to the improvement of such implements that the present invention is directed.

(2) Description of the prior art

One form of implement previously devised for cutting uniform short lengths of yarn from a skein comprises essentially a generally cup-shaped base, preferably of a size to be conveniently held in one hand, and having a rotatable shaft centrally journaled therein.

This shaft is provided with a hub from which a radially disposed arm extends; a handle being attached to the outer end of said arm. Adjacent the hub the radially extending arm carries a fixed blade insert into a recess in the arm adjacent the base.

The closed end of the cup-shaped base is provided with an arcuate channel underlying the blade in the radially extending arm closely adjacent said hub. This channel communicates at one end with an aperture extending through the closed end of the cup-shaped base and is of gradually decreasing depth from that end to its opposite end at which it merges into the flat surface of the closed end of the base.

In the operation of the device, one end of a skein of yarn or strip of material is passed from within the base through the aperture and knotted; the knot lying in the deep end of the channel. The handle is then employed to rotate the arm over the channel from the deep end toward the opposite end; the blade engaging the knot during such operation and drawing it along the channel so that yarn is continuously drawn into the channel through the aperture and wound around the hub.

After several rotations of the arm past the aperture, which will build up a plurality of strands of yarn wound around the hub between the blade and the base, the blade will cut through the strand in contact with it, thus removing the knotted end.

The blade then, upon continued rotation of the arm, engages without immediately cutting through, the next underlying strand to carry it around the hub and draw

2

an additional strand through the aperture in a position underlying those previously so drawn. As the blade reaches the terminal end of the groove, it will again cut through the strand in contact with it, thus forming a short length of material of the length of the channel.

Additional rotations of the arm repeat this operation providing a uniform cut off length of yarn upon each rotation. However, devices of this construction previously manufactured have been capable of producing only one length of cut off yarn pieces and have not always produced clean cuts with different thicknesses of material.

SUMMARY OF THE INVENTION

The present invention provides an improved device of the character described in which means are provided for effecting radial oscillation of the cutting blade during rotation of the handle to effect clean cut-offs of the underlying material and in which, either alternatively or additionally, means are provided for adapting the device to produce cut off pieces of material of any of a plurality of different lengths.

BRIEF DESCRIPTION OF THE DRAWING

FIG. 1 is an exploded perspective view illustrating the elements of an embodiment of the present invention;

FIG. 2 is a side elevational view partially in a central vertical section of the device of FIG. 1 as assembled for operation;

FIG. 3 is a detail view in perspective and partially in compound section of a portion of the base of the device of FIG. 1; and

FIG. 4 is a detail view in perspective and partly in section of the upper portion of the device of FIG. 1.

DESCRIPTION OF THE PREFERRED EMBODIMENT

The preferred embodiment of the invention illustrated in the accompanying drawings comprises a base 10 which is preferably cup-shaped as shown and of a size to be conveniently held in one hand. The base 10 presents a planar surface 12 centrally of which is disposed a post 14 having a portion 16 of reduced diameter extending through a central bore 18 in the base 10 and secured in position by means such as a screw 20 threaded into the portion 16 and washer 22 abutting a portion of the base 10 by means of which the shoulder presented at the inner end of the portion 16 is clamped firmly against the surface 12.

A member 24 is rotatably mounted on the post 14 in contact with the surface 12 and comprises a hub 26 from which an arm 28 extends radially adjacent the surface 12. The member 24 is removably secured in place on the post 14 by means such as a thumb screw 30 threaded into the post 14.

The surface 12 of the base 10 has formed therein an arcuate channel 32 concentrically disposed with respect to the post 14 and hub 26 and communicating adjacent one end with an aperture 34 passing through the base 10. The channel 32 is of gradually decreasing depth from the point at which it communicates with the aperture 34 to its opposite end 36 at which it merges into the planar surface 12 of the base 10.

Carried by the arm 28 in a position overlying the channel 32 is a blade 40 having a sharpened edge 42 on the side adjacent the channel 32. The blade 40 is supported at one end by a pin 44 retained in the arm 28 and at the opposite end by a roller 46 fitting over a depending leg 48 of the blade 40 and within a circular cam track 50 formed in the surface 12 eccentrically with respect to the central opening 18 in the base 10 (see FIG. 3) in a location underlying the hub 26 which is slotted at 51 to receive the blade. The roller 46 thus constitutes a cam follower car-

ried by the blade and disposed in the cam track 50 for effecting radial oscillation of the blade 40 upon rotation of the member 24. Such rotation may be conveniently effected by means of a handle 52 secured to the arm 28 by means such as a screw 54.

Also formed in the planar surface 12 of the base 10 is an additional arcuate channel 60 concentrically disposed with respect to the post 14 and hub 26 radially outwardly of the channel 32. The channel 60 communicates adjacent one end with an aperture 62 (FIG. 3) in the base 10 and is of gradually decreasing depth from the point at which it communicates with the aperture 62 to its opposite end 64 at which it merges into the planar surface 12 of the base 10. The channel 60, like the channel 32, underlies the edge 42 of the blade 40. Each channel extends approximately 345° around the central opening 18.

As will become apparent from the description of the operation of the device hereinafter, an arcuate collar 70 provided with a slot 72 may be removably secured in a position surrounding the hub 26 and overlying the arcuate channel 32, as shown in FIG. 2, by removing the screw 30, sliding the member 24 upwardly over the end of the post 14, placing the collar 70 over the hub 26, and then replacing the member 24 on the post 14 and securing the screw 30 back in place. This is done when it is desired to employ the device to cut longer uniform lengths of material than will be cut when the collar 70 is not in place, as described.

In the operation of the device without the collar 70 in place, the material to be cut into uniform short lengths is fed into the aperture 34 from the interior of the base 10 and the end projecting above the surface 12 is knotted. The member 24 is then rotated by means of the handle 52 in a direction to move the blade 40 carried by the arm 28 from the deep end of the channel 32 toward the end 36 thereof. As this is done, the blade 40 carries along the knotted end of the material, drawing additional material through the aperture 34 into the channel 32. As the knotted end of the material is thus carried back over the aperture 34, the additional material being drawn through the aperture 34 assumes a position underlying the strand originally drawn therethrough, raising the latter upwardly against the side of the hub 26. As the knotted end of the material again is drawn over the aperture 34, a third strand of material will be drawn into the channel 32 underlying the first two, raising them still further upwardly against the side of the hub 26.

Depending upon the thickness of the material to be cut, when approximately three or four strands have been thus built up against the side of the hub 26, the uppermost strand will, as the strands are raised upwardly by the decreasingly shallow channel 32, be pressed sufficiently strongly against the blade edge 42 to cause the blade, which is being constantly oscillated by the eccentric cam track 50 and cam follower 46, to cut through the uppermost strand. The first such cutting operation will merely remove the knotted end of the material, but thereafter on each 360° revolution of the member 24, a uniform length of the material will be cut off.

When it is desired to prepare longer strips of material than can be thus prepared with the device, the collar 70 is put in place, as previously described, being positioned with the blade 40 lying in the slot 72 of the collar 70. When the device is thus assembled, the material to be cut is fed from the interior of the base 10 into the aperture 62 instead of into the aperture 34 and, the channel 32 being covered by the collar 70, the material will, when knotted, be carried by the blade 40 along the channel 60

which, being disposed radially outwardly of the channel 32, is necessarily longer. Thus when the device is operated in otherwise the same manner as described in connection with the description of its operation with the collar removed, the strands of material will be built up against the periphery of the collar 70 rather than against the hub 26, and uniform longer lengths will thus be cut off, one with each rotation of the member 24.

What is claimed is:

1. A device of the character described, having a base presenting a planar surface, a member rotatably mounted thereon having a hub and arm radially extending from said hub adjacent said surface, an arcuate channel in said surface concentrically disposed with respect to said hub, an aperture in said base communicating with said channel adjacent one end thereof; said channel being of gradually decreasing depth between said aperture and a point at which it merges into the planar surface of said base, and a blade carried by said arm and overlying said channel, characterized by the provision of a cam track in said base underlying said hub and eccentrically disposed with respect thereto, and means comprising a cam follower carried by said blade and disposed in said cam track for effecting radial oscillation of said blade upon rotation of said member.

2. A device of the character described according to claim 1, further provided with an additional arcuate channel in said surface concentrically disposed with respect to said hub radially outwardly of said first mentioned channel, an additional aperture in said base communicating with said additional channel adjacent one end thereof, said additional channel also underlying said blade and being of gradually decreasing depth between said additional aperture and a point at which it merges into the planar surface of said base, and a removable arcuate collar surrounding said hub and overlying said first mentioned arcuate channel.

3. A device of the character described, having a base presenting a planar surface, a member rotatably mounted thereon having a hub and arm radially extending from said hub adjacent said surface, an arcuate channel in said surface concentrically disposed with respect to said hub, an aperture in said base communicating with said channel adjacent one end thereof; said channel being of gradually decreasing depth between said aperture and a point at which it merges into the planar surface of said base, and a blade carried by said arm and overlying said channel, characterized by the provision of an additional arcuate channel in said surface concentrically disposed with respect to said hub radially outwardly of said first mentioned channel, an additional aperture in said base communicating with said additional channel adjacent one end thereof, said additional channel also underlying said blade and being of gradually decreasing depth between said additional aperture and a point at which it merges into the planar surface of said base, and a removable arcuate collar surrounding said hub and overlying said first mentioned arcuate channel.
